RAILWAY SWITCH CONTROLLING APPARATUS

Henry S. Young, Wilkinsburg, Pa., assignor to
The Union Switch & Signal Company, Swiss-
vale, Pa., a corporation of Pennsylvania

Application November 24, 1934, Serial No. 754,616
Renewed March 31, 1937

21 Claims. (Cl. 246—3)

My invention relates to railway switch controlling apparatus, and particularly to apparatus of the type involving a polarized relay controlled by a manually operated pole-changer, which 5 lay in turn causes movements of the switch to normal and reverse positions.

One feature of my invention is the use of a polarized relay which is so constructed that its neutral front contacts remain closed while its 10 polar contacts are operated from one extreme position to the other by a quick reversal of polarity of the current supplied to its windings.

The apparatus of my invention is an improvement over that disclosed in the copending applications Serial No. 313,772, filed October 20, 1928, 15 by Howard A. Thompson for Multiple control apparatus; Serial No. 323,286, filed December 3, 1928, by Lester E. Spray, for Multiple control apparatus; Serial No. 416,061, filed December 23, 1929, by Howard A. Thompson for Multiple control apparatus; and Serial No. 695,294, filed October 26, 1933, by Earl M. Allen and Howard A. Thompson for Interlocking control apparatus.

I will describe three forms of apparatus embodying my invention, and will then point out 25 the novel features thereof in claims.

In the accompanying drawing, Fig. 1 is a diagrammatic view showing one form of apparatus embodying my invention for controlling a fluid pressure mechanism M for operating a railway track switch H¹. Fig. 2 is a modification of a portion of the apparatus shown in Fig. 1 for controlling an electric motor mechanism N for operating track switch H¹. Fig. 3 is a modification of a portion of the apparatus shown in Fig. 2 for also controlling an electric motor mechanism N for operating a railway track switch H¹.

Similar reference characters refer to similar parts in each of the views.

Referring first to Fig. 1, the reference characters 1 and 1^a designate the track rails of a stretch of railway track Y which is divided by insulated joints 2 into sections B—C, C—D and D—E. Each of these sections is provided with 30 a track circuit such, for example, as is shown for section D—E, comprising a battery designated by the reference character 3 connected across the rails adjacent one end of the section, and a relay designated by the reference character T connected across the rails adjacent the opposite end 35 of the section.

Located in section D—E, is a switch H¹ for connecting track Y with a second track Z. Switch H¹ is operated by a fluid pressure mechanism M, 40 comprising a normal control magnet nn, a re-

verse control magnet rr, and a master control or lock magnet q. In section C—D, there is a similar switch H².

At point C, a signal S is shown for controlling eastbound traffic movements, that is, traffic 5 movements from left to right, as shown in the drawing, over switches H¹ and H².

Normal and reverse switch control magnets nn and rr for mechanism M are controlled by a polar contact 20 of a polarized switch control relay m in its normal or its reverse position, respectively. Lock magnet q for mechanism M is controlled by back contacts 21 and 22 of normal and reverse indication relays which are designated by the reference characters i and t, 10 15 respectively.

Polarized switch control relay m is so constructed that if the polarity of the current supplied to its windings is quickly reversed, its neutral front contacts operated by its neutral armature will remain closed while its polar contacts are operated by its polar armature from one extreme position to the other. Relay m is controlled by an approach locking relay P, a route locking relay V, track relay T, its own neutral 20 and polar contacts 8, 9 and 12, and pole-changing contacts 4, 10, 11 and 13 of a manually operable device which may be a lever k.

Approach locking relay P may be controlled in any suitable manner such, for example, as shown 30 for relay L in a Patent No. 1,956,851, which was granted May 1, 1934, to C. A. Brooks and J. M. Pelikan, for Railway traffic controlling apparatus. The manner in which relay P is controlled prevents an operator from changing the position of switch H¹ until a measured period of time 35 has elapsed after signal S has been caused to indicate stop, if an eastbound train has entered section B—C while signal S is indicating caution or proceed.

Route locking relay V is so controlled that switch H¹ cannot be operated while an eastbound train occupies section C—D.

Lever k has a normal position n and a reverse position r. Lever k operates four contacts, two 45 of which, contacts 4 and 10 are closed when lever k is in its position n, and the other two of which, contacts 11 and 13, are closed when lever k is in its position r.

On account of relay m having the characteristic that its neutral contacts 8 and 12 remain closed while its polar contact 9 is moved from one of the extreme positions to the other by a quick reversal of polarity of the current supplied to its winding, relay m can be controlled 50 55

by a circuit through either its contact 8 or its contact 12 to operate its polar contact 9 if relays P, V and T are energized, but if one of these relays is deenergized when the operator moves lever *k* from its *n* to its *r* position or from its *r* to its *n* position, relay *m* will not reverse its polar contacts until lever *k* is again placed in the position corresponding to the position of polar contact 9 of relay *m* while all of the relays P, V and T are energized. In this way, control storage for relay *m* is prevented.

Operated in conjunction with switch H^1 is a pole-changer 14. A polarized switch indication relay *h* is so controlled by pole-changer 14 that it becomes energized in the normal or the reverse direction according as switch H^1 is operated to its normal or its reverse position, respectively.

A normal indication relay, designated by the reference character *i*, and a reverse indication relay, designated by the reference character *t*, are associated with switch H^1 . Relay *i* is controlled by a neutral front contact and by a normal polar contact of the polarized indication relay *h* and by a normal polar contact of the polarized control relay *m* as well as by a back contact of reverse indication relay *t*. Relay *t* is controlled by a neutral front and a reverse polar contact of the polarized indication relay *h* and by a reverse polar contact of relay *m* as well as by a back contact of normal indication relay *i*.

Referring now to Fig. 2, an electric motor mechanism N, comprising an armature 33 and a field winding 35, is here shown for operating switch H^1 . Operations of mechanism N are controlled by normal and reverse switch relays *f* and *g*, respectively.

Included in each of the circuits for mechanism N is a pick-up winding 32 of an overload relay W in multiple with a resistor 31. The normal operating current for mechanism N is insufficient to cause relay W to operate its contact 27. Resistor 31 has a positive temperature coefficient of resistance, and hence if mechanism N draws an excessive amount of current as, for example when there is some obstruction to the movement of switch H^1 , resistor 31 will become heated by such excess current, causing an increase in its resistance. Due to the increase in resistance of resistor 31, the current flowing through winding 32 of relay W will be still further increased, causing contact 27 of relay W to be operated by a lower excess current that would otherwise be necessary.

Also operated in conjunction with switch H^1 are normal and reverse switch contacts 26 and 25, respectively. Contact 26 is arranged to be closed at all times except when switch H^1 occupies its reverse position. Contact 25 is arranged to be closed at all times except when switch H^1 occupies its normal position.

In order to select between currents of opposite polarities, there are included, in the circuits for normal and reverse switch relays *f* and *g*, asymmetric units designated by the reference character *a* with distinguishing exponents. These units *a* may be of the well-known copper oxide rectifier valve type. Relays *f* and *g* are also controlled by switch contacts 25 and 26, respectively, and by the back point of contact 27 of relay W as well as by neutral contacts 23 and 29 and polar contacts 24 and 28 of relay *m*. Relay *m* may be controlled exactly as shown in Fig. 1.

Relay W, when mechanism N draws an excessive amount of current, opens its contact 27 at the back point, thereby breaking the circuit for

relays *f* and *g*, and closes its contact 27 at the front point, thereby completing one of the stick circuits for relay W through its holding winding 36. The stick circuits for relay W are so controlled by relay *m* that the current in each stick circuit flows through the holding winding of relay W in the same direction as the current in the corresponding pick-up circuit flows through the pick-up winding of relay W.

In Fig. 3, switch H^1 is shown operated by an electric motor mechanism N as in Fig. 2. Relays *m*, *f* and *g* and holding winding 36 of relay W may be controlled exactly as for Fig. 2.

The operating circuits for mechanism N, constituting also the pick-up circuits for winding 32 of relay W, however, differ from those shown in Fig. 2, in order to provide a snubbing circuit of lower resistance for armature 33 of electric motor mechanism N, involving the use of two resistors 37 and 38 each of which has a positive temperature coefficient of resistance. The normal operating circuit for mechanism N includes resistor 37 in multiple with a series path through resistor 38 and pick-up winding 32 of relay W. The reverse operating circuit for mechanism N includes resistor 38 in multiple with a series path through resistor 37 and in the opposite direction through pick-up winding 32 of relay W.

Having described, in general, each of three forms of apparatus embodying my invention, I now trace in detail the operation of these various forms of apparatus.

As shown in the drawing, all parts are in the normal condition, that is, track relay T is energized; switch lever *k* is in its normal position *n*; switches H^1 and H^2 are in the normal position; signal S is indicating stop; relays *h*, *i*, *m*, P and V, and normal switch control magnet *nn* are energized; and relays *t*, *f*, *g* and W are deenergized.

I will first trace the operation of the form of apparatus shown in Fig. 1.

One circuit by which relay *m* is energized passes from terminal *x* of a suitable source of current not shown in the drawing, through contact 4 of lever *k*, contact 5 of relay P, contact 6 of relay V, contact 7 of relay T, winding of relay *m*, contact 8 of relay *m*, and contact 10 of lever *k* back to terminal *o* of the same source of current. A second circuit which is also closed for relay *m* is the same as the circuit just traced except that it includes contact 9 of relay *m* in its left-hand position instead of contact 8 of relay *m*. Current flowing in each of these circuits is of normal polarity, and hence relay *m* is energized in the normal direction.

On account of switch H^1 being in its normal position, pole-changer 14, operated in conjunction with switch H^1 , is in its normal position, and hence relay *h* is energized by current of normal polarity. With relays *h* and *m* energized by current of normal polarity, normal indication relay *i* is energized by a circuit passing from terminal *x*, through contacts 15 and 16 of relay *h*, contact 17 of relay *t*, winding of relay *i*, and contact 19 of relay *m* to terminal *o*.

With relay *m* energized in the normal direction, normal control magnet *nn* is energized by a circuit passing from terminal *x*, through contact 20 of relay *m* in its left-hand position, and the winding of magnet *nn* to terminal *o*. The circuit for lock magnet *q* is open at contact 21 of relay *i*.

I will assume that with all parts of the apparatus thus in the normal condition, the operator desires to reverse switch H^1 . He will there-

fore move lever k to its reverse position r , completing a circuit for energizing relay m in the reverse direction, this circuit passing from terminal x , through contact 11 of lever k , contact 12 of relay m , winding of relay m , contacts 1, 6 and 5 of relays T , V and P , respectively, and contact 13 of lever k to terminal o . Relay m , being thus energized by current of reverse polarity, will shift its polar contacts 9, 19 and 20 from the normal or left-hand position, as shown in the drawing, to the reverse or right-hand position. Such an operation of relay m can be accomplished if the manipulation of lever k , from its n to its r position, is quick enough to close the reverse operating circuit for relay m through contact 12 of relay m before this contact opens.

With relay m energized in the reverse direction, the circuit for relay i is opened at contact 19 of relay m . Back contact 21 of relay i therefore completes a circuit for lock magnet q , passing from terminal x , through contacts 21 and 22 of relays i and t , respectively, and the winding of magnet q to terminal o . With relay m energized in the reverse direction, reverse control magnet rr will be energized by its circuit passing from terminal x , through contact 20 of relay m in its right-hand position, and the winding of magnet rr to terminal o . With magnets q and rr energized, mechanism M will operate switch H^1 to its reverse position.

Upon the completion of the operation of switch H^1 to its reverse position, pole-changer 14 will be shifted to its reverse position, causing relay h to be energized by current of reverse polarity. With relay h energized by current of reverse polarity and with relay m still energized by current of reverse polarity, a circuit will be completed for energizing reverse indication relay t , passing from terminal x , through contact 15 of relay h , contact 16 of relay h in its right-hand position, winding of relay t , contact 18 of relay i , and contact 19 of relay m in its right-hand position to terminal o . Relay t , upon becoming energized, opens its contact 22, thereby breaking the circuit for lock magnet q .

When the operator desires to return switch H^1 to the normal position, he will return lever k from its r to its n position, causing relay m to again become energized in the normal direction by its circuit previously traced through its own contact 8, although the circuit through its contact 9 is now open. With relay m energized in the normal direction, the circuit traced for relay t will be opened at contact 19 of relay m . The circuit previously traced for lock magnet q will therefore again be closed, and the circuit for normal control magnet nn , previously traced, will again be completed, causing mechanism M to return switch H^1 to its normal position.

Upon the completion of the operation of switch H^1 to its normal position, pole-changer 14 will be returned to its normal position, causing relay h to again be energized by current of normal polarity. With relays h and m energized by current of normal polarity, relay i will again be energized by its circuit previously traced, causing the circuit for magnet q to again be opened at contact 21.

I will next assume that, with all parts again in the normal condition, the operator clears signal S for an eastbound traffic movement over switches H^2 and H^1 . The operation for clearing signal S causes relay P to be deenergized.

I will further assume that a train then enters section $B-C$, and afterward proceeds into section

$C-D$, and then into section $D-E$. While the train is in section $C-D$, relay V will be deenergized, and while the train is in section $D-E$, relay T will be deenergized.

I will also assume that while one of the relays P , V and T is deenergized, the operator, by mistake, attempts to reverse switch H^1 by moving lever k to its r position. With any one of the relays P , V and T deenergized, relay m will also be deenergized, and hence, on account of contact 12 of relay m being open, the operation of lever k to its r position can not complete the reverse energizing circuit for relay m . Assuming that the operator does not return lever k to its normal position, and that all of the relays P , V and T again become energized, the reverse energizing circuit for relay m will still not be completed on account of contact 12 of relay m being open and contact 9 of relay m being in its normal position.

In order to energize relay m in the reverse direction, the operator must return lever k to its n position, thereby completing the normal control circuit for relay m through its polar contact 9 in the left-hand position. This will cause contacts 8 and 12 of relay m to be closed, and the operator can then complete the reverse energizing circuit, previously traced for relay m through its contact 12, by again reversing lever k .

It follows that if the operator changes the position of lever k while one of the relays P , V and T is deenergized, subsequent energization of these relays will not cause relay m to be energized in the direction corresponding to the changed position of lever k , and hence the storage of control for relay m is prevented.

I will next describe the operation of the form of apparatus shown in Fig. 2. With all parts in the normal condition, relay m will be energized in the normal direction as shown in Fig. 1.

I will assume that the operator desires to reverse switch H^1 . He will therefore move lever k to its r position for energizing relay m by current of reverse polarity. With relay m energized by current of reverse polarity, its polar contacts 24 and 28 will be operated to the right-hand position, thereby completing a circuit for energizing reverse switch relay g , passing from terminal x , through contact 23 of relay m , contact 24 of relay m in its right-hand position, back point of contact 27 of relay W , asymmetric units a^3 and a^4 , winding of relay g , contact 26 of switch H^1 , contact 28 of relay m in its right-hand position, and contact 29 of relay m to terminal o .

Relay g , upon becoming energized, completes the reverse operating circuit for mechanism N , passing from terminal x , through the front point of contact 34 of relay g , armature 33 of motor mechanism N , resistor 31 in multiple with winding 32 of relay W , back point of contact 30 of relay f , and field winding 35 of electric motor mechanism N to terminal o . Under normal operating conditions, the current flowing in this circuit will cause mechanism N to move switch H^1 to the reverse position, but will not be of sufficient magnitude to cause relay W to lift the finger of contact 27 from the back point to the front point. Upon the completion of the operation of switch H^1 to the reverse position, contact 26 will be opened, thereby breaking the circuit just traced for relay g .

When the operator desires to return switch H^1 to the normal position, he will return lever k to its n position, causing relay m to again become energized by current of normal polarity. Relay m will thereupon complete a circuit for energiz-

ing normal switch relay f , this circuit passing from terminal x , through contact 23 of relay m , contact 24 of relay m in its normal position, asymmetric units a^1 and a^2 , winding of relay f , contact 25 of switch H^1 which became closed during the operation of switch H^1 to the reverse position, back point of contact 27 of relay W , contact 28 of relay m in its left-hand position, and contact 29 of relay m to terminal o .

10 Relay f , upon becoming energized, completes the normal operating circuit for mechanism N , passing from terminal x , through the front point of contact 30 of relay f , resistor 31 in multiple with winding 32 of relay W , armature 33 of mechanism N , back point of contact 34 of relay g , and field winding 35 of mechanism N to terminal o . Under normal operating conditions, the current flowing in this circuit will cause motor N to return switch H^1 to its normal position, but 20 will be insufficient to cause relay W to move the finger of its contact 27 from the back point to the front point.

I will next assume that, with all parts of the apparatus again in the normal condition, the operator attempts to reverse switch H^1 but that the movement of switch H^1 is obstructed in some manner, such, for example, as by a stone or a piece of coal, so that motor N draws an amount of current in excess of the normal operating current. Such current flowing in the reverse operating circuit previously traced for motor N will cause resistor 31 to be heated, thereby causing the resistance of unit 31 to be increased, and hence still more of the excess current will flow 30 through the winding of relay W until the current is of such a value as to cause relay W to open its contact 27 at the back point and to close this contact at the front point.

With contact 27 closed at the front point, current will flow through holding winding 36 of relay W in the same direction as current flows through pick-up winding 32 of relay W in the reverse operating circuit for motor N , this stick circuit for relay W passing from terminal x , through 40 contact 23 of relay m , contact 24 of relay m in its right-hand position, front point of contact 27 of relay W , winding 36 of relay W , contact 28 of relay m in its right-hand position, and contact 29 of relay m to terminal o . The opening of 50 contact 27 of relay W at its back point breaks the circuit previously traced for reverse switch relay g , causing this relay to become deenergized. The holding circuit traced for relay W through its winding 36 will remain closed until the 55 operator either deenergizes relay m long enough to open its contacts 23 and 29, or energizes relay m by current of normal polarity.

I will now describe the operation of the form of apparatus shown in Fig. 3. I will assume that 60 the operator, desiring to reverse switch H^1 , moves lever k to its r position, causing relay m to be energized in the reverse direction and relay g to become energized.

With relay g energized, the reverse operating circuit for motor mechanism N will be completed, passing from terminal x , through resistor 38 in multiple with the series path through resistor 37 and winding 32 of relay W , front point of contact 34 of relay g , armature 33 of motor N , back point of contact 30 of relay f , and field winding 35 of motor N to terminal o . Under normal conditions of operation, the current flowing in this circuit, although sufficient to cause switch H^1 to be operated to its reverse position, will be 70 insufficient to cause relay W to open its contact 75

27 at the back point and close this contact at its front point.

If, however, the movement of switch H^1 should be obstructed, causing motor N to draw an excessive amount of current, the larger part of such current, flowing through resistor 38, would cause this resistor to become heated. The resistance of unit 38 would, therefore, increase and cause a larger proportion of the current to flow through resistor 37 and winding 32 until 10 relay W would lift the finger of its contact 27 from the back point to the front point. Such operation of contact 27 would cause relay g to become deenergized, thereby breaking the operating circuit for motor N which also constitutes a pick-up circuit for relay W . It will be noted that current in the stick circuit now completed for relay W flows through the winding 36 of relay W in the same direction as current in the operating circuit, just described for motor 20 N , flows through the winding 32 of relay W .

From the foregoing description and the accompanying drawing, it will be understood that with the arrangement of circuits shown for relay m , a novel method is provided for preventing storage of control for a railway track switch. It will also be noted that I have provided a novel method of overload protection for such a switch.

Although I have herein shown and described only three forms of railway switch controlling apparatus embodying my invention, it is understood that various changes and modifications may be made therein within the scope of the appended claims without departing from the spirit and scope of my invention.

Having thus described my invention, what I claim is:

1. In combination, a railway track switch, a polarized relay having a neutral armature and a polar armature, means manually controlled and also controlled by said polar armature for energizing said relay for operating said neutral armature, other means manually controlled and also controlled by said neutral armature for energizing said relay for operating said polar armature from each of its extreme positions to the other, locking means for at times rendering said other means ineffective to energize said relay, and switch operating means controlled by said polarized relay for moving said switch from each of its extreme positions to the other.

2. In combination, a railway track switch, a polarized relay having a neutral armature and a polar armature, means controlled by said polar armature for energizing said relay for operating said neutral armature, other means manually controlled and also controlled by said neutral armature for energizing said relay for operating said polar armature from each of its extreme positions to the other, locking means for at 60 times rendering said other means ineffective to energize said relay, and switch operating means controlled by said polarized relay for moving said switch from each of its extreme positions to the other.

3. In combination, a railway track switch, a manually controllable instrument having a normal and a reverse position, a polarized relay, a neutral armature operated by said relay, a polar armature operated by said relay and having a 70 normal and a reverse control position, means controlled by said instrument and by said polar armature for energizing said relay for operating said neutral armature only when both said instrument and said polar armature are in their 75

- normal positions or when both are in their reverse positions, other means controlled by said neutral armature for energizing said relay for operating said polar armature from each of its 5 control positions to the other, locking means for at times rendering said other means ineffective to energize said relay, said switch operating means controlled by said polarized relay for moving said switch from each of its extreme 10 positions to the other.
4. In combination, a railway track switch, a manually controllable switch lever, a polarized switch control relay having neutral and polar contacts and so constructed that the neutral 15 contacts remain closed when the current supplied to the windings of said relay is reversed in direction, means controlled by normal and reverse polar contacts of said polarized switch control relay for operating said switch to normal 20 and reverse positions respectively, and normal and reverse control circuits for energizing said polarized relay controlled by normal and reverse contacts respectively of said switch lever and also controlled by traffic conditions and including neutral contacts of said relay in multiple 25 with polar contacts of said relay for preventing control storage for said relay.
5. In combination, a railway track switch, a manually controllable switch lever having a normal and a reverse position, normal and reverse contacts of said switch lever closed when said switch lever occupies said normal or said reverse position respectively, a polarized switch control relay having neutral and polar contacts and so 30 constructed that the neutral contacts remain closed when the current supplied to the windings of said relay is reversed in direction and that when said relay is deenergized its polar contacts remain in the position in which they were placed by the last previous energization of said relay, a locking relay, a normal control circuit for said polarized relay controlled by one of its own normal polar contacts and by a normal contact of 35 said lever, a reverse control circuit for said polarized relay controlled by one of its own reverse polar contacts and by a reverse contact of said lever, a second normal control circuit and a second reverse control circuit for said polarized relay controlled by a normal and a reverse contact 40 respectively of said lever and each controlled by a contact of said locking relay as well as by a neutral contact of said polarized relay for preventing storage of control of said polarized relay, and means controlled by normal and reverse polar 45 contacts of said polarized relay for operating said switch to normal and reverse positions respectively.
6. In combination, a stretch of railway track, traffic governing means for controlling traffic 50 movements over said stretch, a polarized control relay having neutral and polar contacts and so constructed that its neutral contacts remain closed when the current supplied to its windings is reversed in direction and that when said relay is deenergized its polar contacts remain in the 55 position in which they were placed by the last previous energization of its windings, a traffic relay controlled by traffic conditions in said stretch, a normal control circuit for said polarized relay controlled by one of its own normal polar contacts, a reverse control circuit for said polarized relay controlled by one of its own reverse polar contacts, a second normal control circuit and a second reverse control circuit for 60 said polarized relay each controlled by said traffic relay and by a neutral contact of said polarized relay for preventing storage of control of said polarized relay, and means controlled by said polarized control relay for supplying said normal and reverse control circuits with current of normal and reverse polarity respectively, and means controlled by said polarized control relay for controlling said traffic governing means to permit a first or a second traffic movement over said stretch according as said polarized control relay is energized by current of normal or of reverse polarity.
7. In combination, a stretch of railway track, traffic governing means for controlling traffic movements over said stretch, a polarized control relay having neutral and polar contacts and so 65 constructed that its neutral contacts remain closed when the current supplied to its windings is quickly reversed in direction but will open if its windings remain deenergized longer than a brief period of time and its polar contacts will remain in the position in which they were placed by the last previous energization of its windings, an auxiliary control contact, means for at times closing and for at other times opening said auxiliary control contact, a normal control circuit for said polarized relay controlled by one of its own normal polar contacts, a reverse control circuit for said polarized relay controlled by one of its own reverse polar contacts, a second normal control circuit and a second reverse control circuit for said polarized relay each controlled by said auxiliary control contact and by a neutral contact of said polarized relay for preventing storage of control of said polarized relay, manually controlled means for supplying said normal and reverse control circuits with current of normal and reverse polarity respectively, and means controlled by said polarized control relay for controlling said traffic governing means to permit a first or a second traffic movement over said stretch according as said polarized control relay is energized by current of normal or of reverse polarity.
8. In combination, a railway track switch, a polarized relay, manually controllable means for energizing said relay by current of normal or of reverse polarity, an overload relay having a pick-up winding responsive only to current of greater magnitude than the normal operating current for said switch and also having a holding winding, a normal and a reverse switch relay, a normal switch contact operated by said switch and closed at all times except when said switch occupies its reverse position, a reverse switch contact operated by said switch and closed at all times except when said switch occupies its normal position, a control circuit for said normal switch relay controlled by said reverse switch contact and by a normal polar contact of said polarized relay as well as by a back contact of said overload relay and including an asymmetric unit to prevent the flow of current in the reverse direction in a given part of said circuit, a control circuit for said reverse switch relay including a portion of the control circuit for said normal switch relay and controlled by said normal switch contact and also by a reverse polar contact of said polarized relay as well as by a back contact of said overload relay and including an asymmetric unit in a given part of the circuit to prevent the flow of current in the normal direction, a normal and a reverse operating circuit for said switch controlled by said normal and reverse switch relays respectively and each including the pick-up winding of said overload relay, and a stick circuit.

cuit for said overload relay controlled by said polarized relay and including the holding winding and a front contact of said overload relay.

9. In combination, a railway track switch, an overload relay having a control winding, a normal and a reverse switch relay, manually controllable means controlled in part by a back contact of said overload relay for selectively energizing said normal and reverse switch relays, a source of current, a resistor having a positive temperature coefficient of resistance and having one of its ends connected to said source of current as well as having its other end connected to one end of said control winding and to a front contact of said normal switch relay, a second resistor having a positive temperature coefficient of resistance and having one of its ends connected to said source of current as well as having its other end connected to the other end of said control winding and to a front contact of said reverse switch relay, a normal operating circuit for said switch including said source of current and said resistors and control winding and also said front contact of the normal switch relay and then passing through the operating mechanisms for said switch and afterwards through a back contact of said reverse switch relay whereby said switch is operated to its normal position and said overload relay is energized sufficiently to operate its contacts if and only if said switch mechanism draws an excessive amount of current, a reverse operating circuit for said switch including said source of current and said resistors and control winding and also said front contact of the reverse switch relay and then passing through the operating mechanism for said switch and afterwards through a back contact of said normal switch relay whereby said switch is operated to its reverse position and said overload relay is energized sufficiently to operate its contacts if and only if said switch mechanism draws an excessive amount of current, and a manually controlled stick circuit for said overload relay including a front contact of said overload relay.

10. In combination, a railway track switch, an overload relay having a control winding, a normal and a reverse switch relay, manually controllable means controlled in part by a back contact of said overload relay for selectively energizing said normal and reverse switch relays, a first and a second resistor each having a positive temperature coefficient of resistance, a normal operating circuit including said first resistor in multiple with a series path through said second resistor and the control winding of said overload relay and controlled by a front contact of said normal switch relay whereby said switch is operated to its normal position if a normal amount of current flows in said normal operating circuit and contacts of said overload relay are operated if and only if a greater amount of current flows, a reverse operating circuit including said second resistor in multiple with a series path through said first resistor and the control winding of said overload relay and controlled by a front contact of said reverse switch relay whereby said switch is operated to its reverse position if a normal amount of current flows in said reverse operating circuit and contacts of said overload relay are operated if and only if a greater amount of current flows, and a manually controlled stick circuit for said overload relay.

11. In combination, a railway track switch, a manually controllable pole-changer comprising a

normal and a reverse contact, an overload relay having a pick-up winding and also having a holding winding, a normal and a reverse control circuit for said switch controlled by said normal and reverse contacts respectively and each including a back contact of said overload relay, a normal and a reverse operating circuit for said switch controlled by said normal and reverse control circuits respectively and each including the pick-up winding of said overload relay whereby the contacts of said overload relay will be operated if the switch should stall and therefore draw an excessive amount of electric current, a normal stick circuit for said overload relay controlled by the normal contact of said pole-changer and including the holding winding as well as a front contact of said overload relay, and a reverse stick circuit for said overload relay controlled by the reverse contact of said pole-changer and including the same holding winding as well as a front contact of said overload relay.

12. In combination, a motor, a manually controllable normal contact, a manually controllable reverse contact, an overload relay having a pick-up winding and a holding winding, a normal and a reverse control circuit for said motor controlled by said normal and reverse contacts respectively and each including a back contact of said overload relay, a normal and a reverse operating circuit for said motor controlled by said normal and reverse control circuits respectively and each including the pick-up winding of said overload relay whereby the contacts of said overload relay will be operated if the motor is energized by current of greater magnitude than its normal operating current, and a normal and a reverse stick circuit for said overload relay controlled by said normal and reverse contacts respectively and including the same holding winding as well as a front contact of said overload relay.

13. In combination, a motor, an overload relay having a pick-up winding and a holding winding, manually controllable normal and reverse operating circuits for said motor and the pick-up winding of said overload relay whereby said overload relay is at times operated to open said operating circuits if said motor is energized by current of greater magnitude than its normal operating current, and manually controllable normal and reverse stick circuits including in common the holding winding of said overload relay for retaining said operating circuits open.

14. In combination, a railway track switch, a manually controllable pole-changer comprising a normal and a reverse contact, an overload relay having a pick-up winding and also having a holding winding, a normal and a reverse control circuit for said switch controlled by said normal and reverse contacts respectively and each including a back contact of said overload relay, a normal and a reverse operating circuit for said switch controlled by said normal and reverse control circuits respectively and each including the pick-up winding of said overload relay whereby the contacts of said overload relay will be operated if the switch should stall and therefore draw an excessive amount of electric current, a stick circuit for said overload relay controlled by said pole-changer and including the holding winding as well as a front contact of said overload relay, and a traffic controlled contact for at times opening said stick circuit.

15. In combination, a railway track switch, a polarized control relay, manually controllable means for energizing said relay by current of nor-

- mal or of reverse polarity, means controlled by traffic conditions for deenergizing said relay when said traffic conditions become unsuitable for said switch to be operated and for preventing subsequent energization of said relay until said traffic conditions again become suitable for said switch to be operated, a normal indication relay, a circuit controlled by a normal polar contact of said control relay and by said switch in the normal position for energizing said normal indication relay, a reverse indication relay, a circuit controlled by a reverse polar contact of said control relay and by said switch in the reverse position for energizing said reverse indication relay, and means controlled by a back contact of said normal indication relay and by a back contact of said reverse indication relay as well as by normal and reverse polar contacts of said control relay for operating said switch to its normal and reverse positions.
16. In combination, a railway track switch, a polarized relay having a neutral armature and a polar armature arranged so that the polarity of current energizing said relay can be reversed without releasing the neutral armature, means manually controlled and also controlled by said polar armature for energizing said relay for operating said neutral armature, other means manually controlled and also controlled by said neutral armature for energizing said relay for moving said polar armature from each of its extreme positions to the other, and switch operating means controlled by said polarized relay for moving said switch from each of its extreme positions to the other.
17. In combination, railway traffic controlling apparatus, a polarized relay having a neutral armature and a polar armature arranged so that the polarity of current energizing said relay can be reversed without releasing the neutral armature, manually controllable means for energizing said relay to operate said neutral armature, means controlled in part by said neutral armature for energizing said relay to operate said polar armature, and means controlled by said polarized relay for selectively operating said traffic controlling apparatus in a first or a second given manner.
18. In combination, railway traffic controlling apparatus, a polarized relay having a neutral armature and a polar armature, manually controlled means for energizing said relay to operate said neutral armature, means controlled in part by said neutral armature for energizing said relay to operate said polar armature, and means controlled by said polarized relay for selectively operating said traffic controlling apparatus in a first or a second given manner.
19. In combination, railway traffic controlling apparatus, a polarized relay having a neutral armature and a polar armature, means controlled in part by said neutral armature for at times energizing said relay to operate said neutral armature, and means controlled by said polarized relay for selectively operating said traffic controlling apparatus in a first or a second given manner.
20. In combination, a polarized relay, means for energizing said relay in the normal or the reverse direction, a motor controlled by said relay and energized in the normal or reverse direction according as the relay is energized in the normal or reverse direction, a device for rendering said motor inoperative upon excessive current flow therein, a single overload winding of said device connected in series with said motor, and a single holding winding of said device energized in the normal or reverse direction when said device is operated according as said relay is energized in the normal or reverse direction.
21. In combination, a polarized relay, means for selectively energizing said polarized relay in the normal and reverse directions, a motor, means for reversibly supplying energy to said motor in accordance with the direction of energization of said polarized relay, a normally released overload relay effective when picked up to prevent the supply of energy to said motor, a winding of said overload relay connected in series with said motor to pick up the overload relay upon excessive current flow in the motor, an auxiliary winding of said overload relay, a circuit for said auxiliary winding including a front contact of said overload relay and a normal polar contact of said polarized relay, another circuit for said auxiliary winding including said front contact and a reverse polar contact of said polarized relay.

HENRY S. YOUNG. 50

CERTIFICATE OF CORRECTION.

Patent No. 2,097,826.

November 2, 1937.

HENRY S. YOUNG.

It is hereby certified that error appears in the printed specification of the above numbered patent requiring correction as follows: Page 5, first column, line 7, claim 3, for the word "said" second occurrence, read and; and that the said Letters Patent should be read with this correction therein that the same may conform to the record of the case in the Patent Office.

Signed and sealed this 25th day of January, A. D. 1938.

(Seal)

Henry Van Arsdale,
Acting Commissioner of Patents.
